UNITED STATES PATENT OFFICE

FERDINAND F. WAECHTER AND LOUIS F. SNYDER, OF PHILADELPHIA, PENNSYLVANIA, ASSIGNORS TO LINK-BELT COMPANY, OF CHICAGO, ILLINOIS, A CORPORATION OF ILLINOIS

CONTROL MECHANISM FOR CRAWLER LOADER BOOMS

Application filed January 25, 1928. Serial No. 249,231.

Our invention relates to improvements in excavating machines and has for one object to provide a control mechanism for a crawler loader boom. Another object of the invention is to provide a control mechanism for that type of crawler loader boom wherein the boom is overweighted at the rear end tending normally to rotate by gravity away from the work and our purpose is to provide means whereby the boom may be longitudinally displaced toward and from the work and at the same time by manipulation of the same displacing means may be rotated from the idle into the working position. Other objects of the invention will appear from time to time in the specification and claims.

The invention is illustrated more or less diagrammatically in the accompanying drawings wherein we have shown only the essential parts of the mechanism; that is, the parts having to do with our present invention and it will be understood that the details of the crawler loader, the boom, the supporting mechanism and the like are adequately illustrated in our co-pending application Serial Number 241,756, filed December 22, 1927.

Figure 1 is a side elevation; Figure 2 is an enlarged section taken on line 2—2 of Figure 1; and Figure 3 is a front elevation.

Like parts are indicated by like characters throughout the specification and drawings.

A is a supporting frame which may be mounted on any suitable truck, carriage or tractor and may be moved by hand or power as desired. A¹ A¹ are downwardly inclined supporting tracks on the front end of the frame A, along which travel flanged rollers A² rotatable on the boom axle A³. A⁴ is an excavator boom pivoted on the axle A³. It will be understood that this boom is adapted to carry the usual type of conveying mechanism such as a belt or chain with buckets and the like and that it is intended to have at the lower end an excavating or digging mechanism of any suitable type which may be operated separately from or in unison with

the conveyor or which may be formed by a part of the conveyor as the case may be. A⁵ is an auxiliary track mounted on the frame A parallel with the tracks A¹ and having a removable cover plate A⁶, there being 65 but one on each end of the frame. A⁷ A⁷ are rollers mounted on brackets A⁸ depending downwardly from the boom adapted to travel along the tracks A⁵ to be held in position thereon by the cover plates A⁶. 60

B B are sheaves mounted rigidly on the outer ends of the axle A¹⁰. B² B² are guide and tilting pulleys mounted on the boom A⁴. B³ is a hoisting and tilting cable dead ended on the axle of the sheave B at the 65 upper end of each of the tracks A¹. This cable extends down by a pulley B⁴ thence up over a sheave B thence down about the tilting pulley B² and thence down to a drum B⁴, there being two of these drums mounted 70 on a single drum shaft B⁵ which shaft carries a gear B⁶ in mesh with a pinion B⁷ which in turn rotates with a gear B⁸ in mesh with a pinion B⁹ adapted to be rotated by a hand wheel B¹⁰ or if preferred by any suitable power means or motor not here shown. Suitable means are provided applied to a drum shaft B⁵ in the form of a brake drum B¹¹ brake band B¹² controlled by a lever B¹³ to lock the drums B⁴ in any suitable position to adjust the boom along the 75 tracks A¹. 80

C C are a pair of limit chains interposed between the upper ends of the tracks and the axle A³ and adapted to prevent movement of the rollers A² and the boom down off the track. 85

It will be understood that the center of gravity of the boom is at a point behind and above the axis of rotation or the supporting line where it is supported on the track by means of the axle so that the boom tends to tilt in a counter clockwise direction toward the horizontal, the boom when in such position raising at its rear end on the frame. This tilting tendency is normally resisted by the cover plates A⁶ engaging the upper sides of the rollers A⁷ and constraining the boom to a rectilinear movement generally along its axis in a direction parallel 90 95

to its tracks A¹ A⁵ and as long as the boom is in the working position and held against rotation manipulation of the drive wheel B¹⁰ drawing or paying out on the cable B³ 5 serves merely to move the boom back and forth in a direction parallel to the tracks limited at its upper end by engagement with the sheaves B B¹ and at its lower end by the limit chains.

10 When it is desired to collapse the boom the operator will lower the boom either until the limit chain supports the load or until the end of the boom rests on the ground. He will then remove the cover plates A⁶ 15 which may be held in place by any suitable means such as bolts, lugs or the like and thus leave the rollers A⁷ free to rotate with the boom away from the track A⁵. If the downward thrust component of the 20 boom along the track is supported by the limit chains and if the cable B³ is tight, the cable extending from the sheave B² from the drum B⁴ will resist its rotation and the operator will then pay out on the cable.

25 Since the limit chains permit no further movement of the sheave B¹ away from the sheave B, this paying out of the cable will permit the boom to rotate toward a horizontal position of rest. If on the other 30 hand the boom is resting on the ground and the chains are not carrying the load as soon as the operator pays out on the cable B³ the boom will tend to rotate and will at the same time tend to travel down along 35 the track and it will continue this downward travel along the track until the limit chains have been brought into tension at which time further movement along the track will cease and the boom will be limited to a 40 rotary movement.

When the operator wishes to return the boom to the working position he will merely pull down on the cable tilting the boom until the auxiliary rollers A⁷ are brought into 45 engagement with the tracks, the cover plate will be replaced and then by manipulation of the cable the boom can be operated toward and from the work in the usual manner.

50 We claim:

1. In a material handling device, an inclined track, a boom pivotally and longitudinally movable therealong, means for moving the boom upwardly along a track 55 and for angularly displacing it, said means being operative to angularly displace the boom only when it is in its extreme downward position.

2. In a material handling device, an inclined track, a boom, pivotally and longitudinally movable therealong, means for limiting its downward movement therealong, means for moving the boom upwardly along the track and when the boom is in 65 its extreme downward position only for an-

gularly displacing it, the center of gravity of the boom being located above its pivot point.

3. In a material handling device, an inclined track, a boom, pivotally and longitudinally movable therealong, means for limiting its downward movement therealong, means for moving the boom upwardly along the track and when the boom is in its extreme downward position only for 70 angularly displacing it, the boom raising and pivot controlling means comprising a cable, sheaves on boom and track over which the cable travels and a separate sheave on the boom at a point removed from its pivot point over which the cable travels. 75

4. In a material handling device, an inclined track, a boom, pivotally and longitudinally movable therealong, means for limiting its downward movement therealong, means for moving the boom upwardly along the track and when the boom is in its extreme downward position only for angularly displacing it, the center of gravity of the boom being located above its pivot point, the boom raising and pivot controlling means comprising a cable, sheaves on boom and track over which the cable travels and a separate sheave on the boom at a point removed from its pivot point over which the 80 cable travels. 85

5. In a material handling device, an inclined track, a boom pivotally and longitudinally movable therealong, a limit chain interposed between the boom and the track to positively limit its downward movement along the track, a sheave associated with the track, a sheave located at the center of rotation of the boom, a sheave located on the boom at a point removed from its center, a cable passing about all said sheaves, means removed from the track for hauling in on the free ends of the cable whereby when the boom is supported by the limit chain the cable may be manipulated to control the rotation of the boom. 90 95 100

6. In a material handling device, an inclined track, a boom pivotally and longitudinally movable therealong, a limit chain interposed between the boom and the track 115 to positively limit its downward movement along the track, a sheave associated with the track, a sheave located at the center of rotation of the boom, a sheave located on the boom at a point removed from its center, a cable passing about all said sheaves, means removed from the track for hauling in on the free ends of the cable whereby 120 when the boom is supported by the limit chain the cable may be manipulated to control the rotation of the boom, the center of gravity of the boom being on the side of the pivot thereof opposed to the last mentioned sheave. 125

7. A loader comprising a support, a down- 130

wardly and forwardly inclined track thereon, a boom, rollers interposed between the boom and the track, excavating and loading machinery carried by the boom, the center of gravity of the boom being so positioned with respect to the supporting rollers that it tends to rotate out of the working toward a general horizontal position, a cable associated with the support and the boom and adapted to move the boom upwardly along the track and a limit chain interposed between the boom and the track for limiting the downward movement of the boom.

8. A loader comprising a support, a downwardly and forwardly inclined track thereon, a boom, rollers interposed between the boom and the track, excavating and loading machinery carried by the boom, the center of gravity of the boom being so positioned with respect to the supporting rollers that it tends to rotate out of the working toward a general horizontal position, a cable associated with the support and the boom and adapted to move the boom upwardly along the track and a limit chain interposed between the boom and the track for limiting the downward movement of the boom, means interposed between the cable and the boom whereby the tension on the cable when the boom is supported by the limit chain may be used to rotate the boom downwardly toward the working position.

9. A loader comprising a supporting frame, an inclined track thereon, a sheave at the upper end thereof, a boom, a roller interposed between it and the track, a sheave concentric with the roller on the boom, a sheave at a point removed from the center of rotation of the boom, a hoisting mechanism on the support, a cable traveling about said sheaves and terminating at the hoisting mechanism, a limit chain interposed between the boom and track to positively limit the downward movement of the boom therealong.

10. A loader comprising a supporting frame, an inclined track thereon, a sheave at the upper end thereof, a boom, a roller interposed between it and the track, a sheave concentric with the roller on the boom, a sheave at a point removed from the center of rotation of the boom, a hoisting mechanism on the support, a cable traveling about said sheaves and terminating at the hoisting mechanism, a limit chain interposed between the boom and track to positively limit the downward movement of the boom therealong, an auxiliary track on the support and a roller on the boom adapted to be brought into engagement with said track, means associated with said last track for constraining the roller to a path parallel therewith.

11. A loader comprising a supporting frame, an inclined track thereon, a sheave at

the upper end thereof, a boom, a roller interposed between it and the track, a sheave concentric with the roller on the boom, a sheave at a point removed from the center of rotation of the boom, a hoisting mechanism on the support, a cable traveling about said sheaves and terminating at the hoisting mechanism, a limit chain interposed between the boom and track to positively limit the downward movement of the boom therealong, an auxiliary track on the support and a roller on the boom adapted to be brought into engagement with said track means associated with said last track for constraining the roller to a path parallel therewith, said means being releasable.

12. In a material handling device, an inclined track, a boom pivotally and longitudinally movable therealong, means independent of the track for limiting its downward movement therealong, means for moving the boom upwardly along the track and for rotating the boom about its pivot point the boom when rotating being supported only at its central portion.

13. In a material handling device, an inclined track, a boom pivotally and longitudinally movable therealong, means independent of the track for limiting its downward movement therealong, means for moving the boom upwardly along the track and for rotating the boom about its pivot point, said rotating means being effective only when the boom is at its extreme lower position.

14. In a material handling device, a track, a boom pivotally and longitudinally movable therealong, means independent of the track for limiting the movement of the boom therealong and means for rotating the boom about its pivot on the track the boom when rotating being supported only at its central portion.

15. In a material handling device, a track, a boom pivotally and longitudinally movable therealong, means independent of the track for limiting the movement of the boom therealong and means for rotating the boom about its pivot on the track, said means being effective only when the boom is at one end of its excursion along the track.

16. In a material handling device, an inclined track, a boom pivotally and longitudinally movable therealong, means interposed between the boom and the track to positively limit its downward movement along the track, a sheave associated with the track, a sheave located at the center of rotation of the boom, a sheave located on the boom at a point removed from its center, a cable passing about all said sheaves, means removed from the track for hauling in on the free ends of the cable whereby when the boom is supported by the limit

chain the cable may be manipulated to control the rotation of the boom.

17. In a material handling device, an inclined track, a boom pivotally and longitudinally movable therealong, means interposed between the boom and the track to positively limit its downward movement along the track, a sheave associated with the track, a sheave located at the center of rotation of the boom, a sheave located on the boom at a point removed from its center, a cable passing about all said sheaves, means removed from the track for hauling in on the free ends of the cable whereby when the boom is supported by the limit chain the cable may be manipulated to control the rotation of the boom, the center of gravity of the boom being on the side of the pivot thereof opposed to the last mentioned sheave.

18. A loader comprising a support, a downwardly and forwardly inclined track thereon, a boom, rollers interposed between the boom and the track, excavating and loading machinery carried by the boom, the center of gravity of the boom being so positioned with respect to the supporting rollers that it tends to rotate out of the working toward a general horizontal position, a cable associated with the support and the boom and adapted to move the boom upwardly along the track and means interposed between the boom and the track for limiting the downward movement of the boom.

19. A loader comprising a support, a downwardly and forwardly inclined track thereon, a boom, rollers interposed between the boom and the track, excavating and loading machinery carried by the boom, the center of gravity of the boom being so positioned with respect to the supporting rollers that it tends to rotate out of the working toward a general horizontal position, a cable associated with the support and the boom and adapted to move the boom upwardly along the track and means interposed between the boom and the track for limiting the downward movement of the boom, means interposed between the cable and the boom whereby the tension on the cable when the boom is supported by the limit means may be used to rotate the boom downwardly toward the working position.

20. A loader comprising a supporting frame, an inclined track thereon, a sheave at the upper end thereof, a boom, a roller interposed between it and the track, a sheave concentric with the roller on the boom, a sheave at a point removed from the center of rotation of the boom, a hoisting mechanism on the support, a cable traveling about said sheaves and terminating at the hoisting mechanism, means inter-

posed between the boom and track to positively limit the downward movement of the boom therealong.

21. A loader comprising a supporting frame, an inclined track thereon, a sheave at the upper end thereof, a boom, a roller interposed between it and the track, a sheave concentric with the roller on the boom, a sheave at a point removed from the center of rotation of the boom, a hoisting mechanism on the support, a cable traveling about said sheaves and terminating at the hoisting mechanism, means interposed between the boom and track to positively limit the downward movement of the boom therealong, an auxiliary track on the support and a roller on the boom adapted to be brought into engagement with said track, means associated with said last track for constraining the roller to a path parallel therewith.

22. A loader comprising a supporting frame, an inclined track thereon, a sheave at the upper end thereof, a boom, a roller interposed between it and the track, a sheave concentric with the roller on the boom, a sheave at a point removed from the center of rotation of the boom, a hoisting mechanism on the support, a cable traveling about said sheaves and terminating at the hoisting mechanism, means interposed between the boom and track to positively limit the downward movement of the boom therealong, an auxiliary track on the support and a roller on the boom adapted to be brought into engagement with said track means associated with said last track for constraining the roller to a path parallel therewith, said means being releasable.

Signed at Philadelphia, county of Philadelphia and State of Pennsylvania, this 17th day of January, 1928.
